UNITED STATES PATENT OFFICE.

ELMER T. WALDSCHMIDT, OF PITTSBURGH, PENNSYLVANIA.

DESIGN FOR A BADGE.

Application filed July 13, 1925. Serial No. 14,074. Term of patent 14 years.

To all whom it may concern:

Be it known that I, ELMER T. WALDSCHMIDT, a citizen of the United States of America, residing at Pittsburgh, in the county of Allegheny and State of Pennsylvania, have invented a new, original, and ornamental Design for a Badge, of which the following is a specification, reference being had to the accompanying drawing, forming a part hereof.

Figure 1 is a front elevation of a badge, showing my new design.

Figure 2 is an edge view thereof.

What I claim is:

The ornamental design for a badge, as shown.

ELMER T. WALDSCHMIDT.
